LAMINAR GUN SIGHT

Thomas A. Quinn, Merrillville, Ind. (5731 Baylor Ave.,
Youngstown, Ohio 44515), and Jack E. Gutridge,
533 214th St., Dyer, Ind. 46311

Filed Feb. 6, 1969, Ser. No. 15,676

Term of patent 14 years

Int. Cl. D22—02

U.S. Cl. D22—8

Fig. 1.

Fig. 2.

Fig. 3.

FIG. 1 is a perspective view of a laminar gun sight showing our new design; and

FIG. 2 is an end elevation thereof on a reduced scale;

FIG. 3 is a side elevation thereof on a reduced scale, the opposite side having substantially the same appearance.

The front surface of the gun sight is shaded to indicate color contrast.

We claim:

The ornamental design for a laminar gun sight, as shown and described.
